CUSHIONED CHAIR

Jean P. Giacomini, York, Pa., assignor to Thonet Industries, Inc., New York, N. Y., a corporation of Delaware

Application June 26, 1957, Serial No. 46,751

Term of patent 14 years

(Cl. D15—1)

FIG. 1

FIG. 2

Fig. 1 is a side perspective view of a chair showing my new design.

Fig. 2 is a top plan view of one arm of the chair shown in Fig. 1, the same being the arm attached to the side of the chair which is forwardmost in Fig. 1.

The characteristic features of my design are shown by means of full lines in the drawing.

The side opposite that shown is of similar appearance.

I claim:

The ornamental design for a cushioned chair, as shown and described.
